United States Patent Office

Des. 206,154
Patented Nov. 8, 1966

206,154

CHAIR OR SIMILAR ARTICLE

Hall V. V. Bradley, Pasadena, Calif., assignor to Brown-Jordan Company, El Monte, Calif., a corporation of California

Filed Apr. 6, 1965, Ser. No. 84,634

Term of patent 3½ years

(Cl. D15—1)

FIG. 1 is an isometric view of a chair showing my new design;

FIG. 2 is a side elevational view;

FIG. 3 is a bottom view;

FIG. 4 is a rear view; and

FIGS. 5, 6, 7, 8, 9, and 10 are fragmentary, enlarged sectional views taken along lines 5—5, 6—6, 7—7, 8—8, 9—9, and 10—10 respectively of FIG. 1.

I claim:

The ornamental design for a chair or similar article, substantially as shown.
